United States Patent Office

Des. 188,154
Patented June 7, 1960

188,154

MOBILE COOKING AND SERVING UNIT

William H. Frick, 850 Euclid Ave., Cleveland, Ohio

Filed Jan. 7, 1959, Ser. No. 54,066

Term of patent 14 years

(Cl. D81—10)

Fig. 1

Fig. 2

Fig. 3

Fig. 1 is a perspective view of the mobile cooking and serving unit embodying my new design, showing the front and one end thereof;

Fig. 2 is a rear elevation thereof;

Fig. 3 is an elevation of the end opposite to that shown in Fig. 1.

I claim:

The ornamental design for a mobile cooking and serving unit, as shown.
